UNITED STATES PATENT OFFICE.

HENRY P. ROBERTS, OF JAMESTOWN, NEW YORK, ASSIGNOR TO HIMSELF
AND AUGUSTUS KIBLING, OF SAME PLACE.

SHOE-MAKER'S JACK.

SPECIFICATION forming part of Letters Patent No. 268,537, dated December 5, 1882.

Application filed April 26, 1882. (No model.)

To all whom it may concern:

Be it known that I, HENRY P. ROBERTS, of Jamestown, in the county of Chautauqua and State of New York, have invented new and useful Improvements in Shoe-Maker's Jacks; and I do hereby declare that the following is a full, clear, and exact description thereof, reference being had to the accompanying drawings, which form a part of this specification.

10 The nature of this invention relates to certain new and useful improvements in the construction of that class of implements ordinarily denominated "pegging-jacks," designed for use in the manufacture of boots and shoes.

15 The invention consists in the peculiar construction, arrangement, and combination of the various parts, whereby it may be adjusted to varying positions, as the work being done may require, all as more fully hereinafter set forth.

20 Figure 1 is a perspective view of my improved jack, and Fig. 2 is a cross-section.

In the accompanying drawings, A represents a flanged swivel-plate, which is designed to be rigidly secured by means of bolts or otherwise 25 to the floor or other convenient place of easy access to the workmen; and this swivel-plate carries the swivel B, to the upwardly-projecting lug a of which is pivotally secured the arm C, the outer end of which terminates in the 30 flanged plate D, in the upper flange of which are formed the teeth b, thus producing an annular ratchet. Upon the top of this plate D, and within the flange thereof, is pivoted the plate E, which carries the vertical arm F and the curved arm G, as shown.

To the arm F is secured the double spring-pawl H, either arm of which may be made to engage with the ratchet b, and upon the outer end of a curved arm, G, is adjustably secured 40 the pad I, which is designed to support the fore part of the last. To the upper end of the arm F is pivotally secured the heel-arm J, which carries the pin d, and which is designed to engage with a hole in the heel of the last. 45 This arm J is also provided with an outwardly-projecting stud, e, between which and the top of the arm F is secured a coil or other suitable spring, K.

In the bottom of the swivel-plate A is placed a loose bearing, h, upon which the swivel B rests and has a bearing, and which enables the jack to be swung around in order that the work may be more readily got at; and through the flange of the plate A is tapped a screw, L, the inner end of which, when so desired, is brought in contact with the edge of the swivel-plate B to prevent its turning. A similar bolt, M, is tapped through the curved arm C, and is designed to engage with the stud a of the swivel-plate, so as to hold or retain the jack in its vertical radial adjustable position.

By this construction and arrangement of parts I produce an implement for shoe-makers' use for holding a boot or shoe in varying positions while it is being worked upon; and it can readily be seen that the jack can be adjusted so that the workmen can inseam, stitch, peg, trim, and finish much faster and easier, and make more solid work than where such work is held upon the knees with a strap, as in the ordinary manner.

What I claim as my invention is—

1. In a shoemaker's jack, the combination of the swivel-plate A, swivel B, having perforated ear a, and the loose bearing-plate h for such swivel, with the arm C, set-screws L M, and last-holding devices, the whole adapted to allow oscillatory adjustment in two directions, as set forth.

2. The adjustable arm C and plate D, having flange and ratchets b, the curved arm G, carrying adjustable toe-pad I, and central pivot, K', combined with the arm F, carrying the heel-pin d, and with the double pawl H, as and for the purpose set forth.

3. The heel-arm J, pivoted to the arm F, and having a perforated ear, e, and heel-pin d, combined with the spring K, arm F, arm G, toe-pad I, and the swivel-arm C, substantially as and for the purpose specified.

HENRY P. ROBERTS.
